UNITED STATES PATENT OFFICE.

JAMES TIMMS AND JAMES O. TIMMS, OF COLUMBUS, OHIO.

CAR-COUPING.

No. 835,581.

Specification of Letters Patent.

Patented Nov. 13, 1906.

Application filed July 2, 1906. Serial No. 324,378.

to all whom it may concern:

Be it known that we, JAMES TIMMS and JAMES O. TIMMS, residents of Columbus, in the county of Franklin and State of Ohio, 5 have invented certain new and useful Improvements in Car-Couplings; and we do hereby declare the following to be a full, clear, and exact description of the invention, such as will enable others skilled in the art to 10 to which it appertains to make and use the same.

Our invention relates to improvements in car-couplings, the object of the invention being to provide improved mechanism for unlocking the pivoted knuckle of couplers of the Janney type and also throwing the knuckle open; and the invention consists in certain novel features of construction and combinations and arrangements of parts, as 20 will be more fully hereinafter described, and pointed out in the claims.

In the accompanying drawings, Figure 1 is a view in vertical cross-section illustrating our improvements. Fig. 2 is a similar view 25 showing the locking-pin in lock-set position and the device ready to force the knuckle open. Fig. 3 is a view of the bar 11; and Figs. 4, 5, 6, 7, and 8 are views illustrating modifications.

30 1 represents a coupling-head; 2 a locking-pin therein, and 3 the tail of a pivoted or swinging knuckle secured against swinging movement by the locking-pin. The lower end of the locking-pin 2 when in locked position projects through an opening in the bottom of the coupling-head, and the pin is made with a shoulder 4 near its lower end to rest on a ledge 5 at the bottom of the head 1 to support the pin 2 in lock-set position with 35 the recess 6 in the pin in line with the knuckle-tail 3 to permit the knuckle to be swung open, and the swinging open of the knuckle-tail will move the pin from lock-set and into position to fall and lock the knuckle when the latter is 40 closed.

45 A lever 7 is pivoted between its ends to a depending lug 8 on the bottom of head 1, and its heavier end projects below pin 2 and is made with an upwardly-curved extreme end, 50 as shown at 9, to engage the curved lower end of pin 2, so that when the lever is swung on its fulcrum the curved end of the lever 7 will not only elevate pin 2 to unlock the knuckle but will also force the pin over to one side due 55 to the cam action of the lever against the pin to bring its shoulder 4 over the ledge 5 and

support the pin in lock-set position. The other end of lever 7, which is approximately vertical, extends up beside the head 1 and projects through an elongated slot 10 in a 60 push-bar 11, the latter being supported in an opening 12 in the wall of head 1 and projecting into a recess 13 in the rear of knuckle-tail 3, provided to receive the same. The outer or free end of push-bar 11 may be supported 65 in any approved bracket or bearing at the end of the car, as this bar 11 has no vertical or pivotal movement, its only movement being longitudinal, and it preferably terminates near the side of the car in convenient reach of an operator. The upper end of lever 7, 70 which projects through the slot in bar 11, is enlarged and given the peculiar curvature or contour shown at 15, which insures the retention of the lever in the slot 10 and prevents 75 possibility of accidental disconnection.

The operation of our improvements is as follows: The bar 11 is first drawn outward, which motion, due to the fact that the upper end of lever 7 projects through the slot 10 in 80 the bar 11, will cause said lever to pivot and its heavier lower end to rise, elevating pin 2, and owing to the cam action of the curved or enlarged end 9 against the curved lower end of pin 2 will force the pin over to one side to 85 bring the shoulder 4 on the pin over the ledge 5 and support the pin in lock-set position. The push-bar 11 is then forced inward, and its inner end will engage the tail of the 90 knuckle and force the knuckle open.

95 In the modification illustrated in Figs. 4, 5 and 6 the upper end of lever 7 is made with a slot or opening 16, the upper portion of said opening being larger than the lower portion 17, and the push-bar 11 is provided with a contracted portion 18 with shoulders 19 at the opposite ends of the contracted portion 18. The bar 11 can be readily inserted in the enlarged opening 16, and the contracted portion will fall into the contracted part 17 of the said opening, the shoulders 19 compelling the lever 7 to be swung by the push-bar, and the opposite sides of the lever at the contracted opening 17 are cut out, forming receptacles or recesses for the shoulders 19 on bar 11 to prevent upward movement of the bar during the normal operation of the improvements; or the lever and push-rod may be constructed to interlock, as shown in Figs. 7 and 8, in which the lever is provided with an elongated slot 20 to receive the flattened end of the push-bar, and the latter is provided 105 110

with a contracted circular portion 21 of substantially the diameter of the slot, so that when the contracted portion 21 is in the slot and the rod given a quarter-turn the rod and lever will be invariably coupled together.

The push-rod 11 is supported in an inclined position, so that the rod will move longitudinally by gravity against the knuckle-tail and remain in such position ready to push the knuckle open when desired. This insures the return of the push-rod against the tail of the knuckle after the lever 7 has been swung on its fulcrum to move the locking device to lock-set position and the lever 7 will return by gravity to its normal position when the push-rod moves inward.

A great many other slight changes might be made in the general form and arrangement of the parts described without departing from our invention, and hence we do not restrict ourselves to the precise details set forth but consider ourselves at liberty to make such slight changes and alterations as fairly fall within the spirit and scope of our invention.

Having fully described our invention, what we claim as new, and desire to secure by Letters Patent, is—

1. The combination with a coupler having a swinging knuckle and a locking device to secure the knuckle in locked position, of a lever fulcrumed to the outside of the coupler and constructed to engage the locking device to move the same to unlocking or lock-set position, and a push-bar constructed to move the lever, said push-bar supported at one end by the wall of the coupling-head back of the knuckle-tail to push the knuckle open when the push-bar is forced inward.

2. The combination with a coupler, a swinging knuckle in said coupler having a tail at its inner end, and a coupling-pin projecting through the bottom of the coupler and located in the path of the knuckle-tail to lock the knuckle in closed position, of a lever fulcrumed to the outside of the coupler and having one end resting below the locking-pin, a push-bar supported in an opening in the wall of the coupler back of the knuckle-tail and

projecting into a recess in the latter, and said bar and lever constructed to interlock to compel them to move together only when the push-rod is pulled outward.

3. The combination with a Janney-type coupler, of a lever fulcrumed between its ends to the outside of the coupler and having one end below and in position to engage the lower end of the knuckle-locking pin, a push-bar supported in an opening in the wall of the coupler back of the knuckle-tail, and said bar slotted to receive the enlarged upper end of the lever.

4. In a car-coupler, the combination with a draw-head having an opening in its wall, a swinging knuckle a locking device, and a lever fulcrumed on the draw-head, one end of the lever being adapted to engage the locking device and move it to its unlocked and lock-set positions, of a push-bar projecting through the opening in the draw-head and supported at one end by the bottom wall of said opening so as to be disposed at a point in rear of the knuckle-tail, the push-bar being connected with said lever and arranged to have a lengthwise movement imparted thereto for pushing the knuckle open.

5. In a car-coupler, the combination with a swinging knuckle, of a push-bar supported at its inner end on the draw-head in rear of the knuckle and adapted to have a sliding movement on the wall of the draw-head, the outer end of the push-bar being supported at a sufficient elevation to cause the bar to slide inwardly by gravity, after it has been pulled outwardly to unlock the knuckle, and thereby return to its position for throwing the knuckle open by having an endwise movement imparted thereto, substantially as set forth.

In testimony whereof we have signed this specification in the presence of two subscribing witnesses.

JAMES TIMMS.
